UNITED STATES PATENT OFFICE.

RAYMOND L. PLUMLEY, OF WILMINGTON, DELAWARE, ASSIGNOR TO FREDERICK OSANN COMPANY, OF NEW YORK, N. Y., A CORPORATION OF NEW YORK.

WORK FEEDING AND GUIDING MECHANISM.

1,214,950.

Specification of Letters Patent. Patented Feb. 6, 1917.

Application filed April 17, 1915. Serial No. 21,986.

To all whom it may concern:

Be it known that I, RAYMOND L. PLUMLEY, a citizen of the United States of America, residing in Wilmington, county of New Castle, and State of Delaware, have invented certain new and useful Improvements in Work Feeding and Guiding Mechanisms, of which the following is a true and exact description, reference being had to the accompanying drawings, which form a part thereof.

My present invention comprises improvements in the work feeding and guiding mechanism for sewing machines, especially devised for use in sewing machines of the type known as straw sewing machines intended for high speed operation in factory use, and the general object of my invention is to provide simple and effective work guiding mechanism capable of ready adjustment both to compensate for wear and to accommodate the different kinds of work and in which the parts liable to the most rapid wear are readily renewable.

The various features of novelty which characterize my invention are pointed out with particularity in the claims annexed to and forming a part of this specification. For a better understanding of the invention, however, and of the advantages possessed by it reference should be had to the accompanying drawings and descriptive matter in which I have illustrated and described the preferred embodiment of my invention.

Of the drawings:

Figure 1 is a side elevation of a straw sewing machine embodying my invention;

Fig. 2 is a partial end elevation of the sewing machine shown in Fig. 1;

Fig. 3 is a partial section on the line 3—3 of Fig. 2;

Fig. 4 is a plan view partly in section on the line 4—4 of Fig. 2;

Fig. 5 is a partial section on the line 5—5 of Fig. 4;

Fig. 6 is a partial section on the line 6—6 of Fig. 4;

Fig. 7 is a partial section on the line 7—7 of Fig. 4; and

Fig. 8 is a plan view of one of the guide plates employed.

In the drawings: A represents the frame of the sewing machine of the type in which the main driving shaft B carries an eccentric connected to a needle lever C by a connecting rod X. The needle lever C is connected to and reciprocates the needle bar D which, with the parallel presser bar E, are both mounted in the arm of the machine frame. Inasmuch as the invention claimed herein pertains solely to the work feeding and guiding mechanism, no further reference to the stitch forming mechanism located above the work plate or bed a, need be made. Such mechanism moreover is described in some detail in my application, Serial No. 21985 filed of even date herewith.

The presser foot F is secured to the lower end of the presser bar and extends generally parallel to the top of the work plate a. Secured to the presser foot F proper and really forming a part thereof, is a plate G formed with a vertical portion or fin G' for engaging the edge of one of the two pieces of work to be joined. In the practical use of the invention in the manufacture of straw hats, for instance, the work piece having its edge engaging the guide fin G' is the previously formed portion Y of the hat. This previously formed portion Y passes over an extension G² of the plate G (see Figs. 1 and 2) and is separated by this extension from the strip of braid Y' to be sewed to the previously formed portion Y. This strip of braid Y' passes between, and is engaged at its opposite edges by the guide plates I and J carried by the adjustable work guide member H. g represents the usual means employed for locking the plates F and G together in the desired adjustment.

The work guiding member H is formed with a key way H² in its under side fitting over the key rib a' on the work plate a. The member H is formed with a longitudinal slot H' through which passes a screw stud L² on which is journaled a knob L. The latter is provided at its inner end with a spur gear L' meshing with rack teeth formed on the member H. With this construction the member H is moved longitudinally, by the rotation of the knob L, to vary the distance between the fin G' and the

guide plate J. In order to provide a frictional holding device for holding the member H and knob L against accidental displacement from any positions into which they have been adjusted, a spring L³ is mounted in a socket formed in the knob L to act between the inner end wall of said socket and the head of the screw stud or stationary axle member L². The knob L is thereby caused to press against the member H and to press the latter against the member A whereby the member H is frictionally held in the different positions into which it is adjusted. Interposed between the spur gear L' and the member H is the washer like head K' of a stationary guide K. The body of the latter is in the form of a rod comprising an inturned end portion and a straight body portion passing freely through an aperture in the flange H³ formed at the end of the member H. The guide or wear plate J is clamped against the flange H³ by means of a clamping screw J². The guide plate I is loosely connected to the member H by means of the shank I' received in a corresponding socket formed in the member H. Advantageously the shank I' is split so that the plate I is frictionally held against displacement while at the same time the plate I may be quickly adjusted to accommodate braids of different widths. With the construction described it is a simple matter to renew the plate J which is preferably formed of sheet metal, whenever wear makes this desirable, without renewing the member H which, is ordinarily a cast metal part and is not subjected to appreciable wear, and will consequently last indefinitely.

40 The work feeding mechanism proper comprises an eccentric B' on the main shaft B, and a connecting rod M by which the throw of the eccentric B' is imparted to a rocker N, and a feed bar P pivotally connected to the rocker N through the stud shaft O and in engagement at its opposite end with the feed lift eccentric, or rather crank pin portion B² of the main shaft B. As shown, the connecting rod M is pivotally connected to the rocker N by means of a stud M' adjustably secured in the arc shaped slot N' formed in the rocker N. The feed bar P is formed with a split ear clamp by means of which the stud shaft O is normally rigidly connected to the feed bar. The stud O is journaled in an adjustable bearing formed in the rocker N. The connection between the feed bar P and the crank pin portion B² of the main shaft 50 comprises a split bushing Q, the two halves of which each have their convex sides flattened so that the bushing and crank pin B² as a whole, forms a block slidingly received in the guideway P² between the offset bifurcations P' at the corresponding end of the

feed bar P. These bifurcations may be drawn together to compensate for wear and to secure the desired tightness of the connection between the bar P by a clamping screw P³. P⁴ represents a shim interposed between the bifurcations P' to fix the distance between the bifurcations in any adjustment, the thickness of the shim being varied for different adjustments. When the bifurcations P' are drawn together compensation is made not only for wear of the contacting surfaces of parts P' and A, but for wear at the contacting surfaces of pin B² and bushing Q.

The bushing Q is held against endwise displacement by engagement with the shoulder at the end of the crank pin portion B² formed by the body of the shaft B, and by the shoulder B⁴ formed on the main shaft or on the hook S secured to the main shaft. The feed bar P has adjustably secured to it the feed jaw R.

While in accordance with the provisions of the statutes I have illustrated and described the best form of my invention now known to me, it will be apparent to those skilled in the art that changes may be made in the form of apparatus disclosed without departing from the spirit of my invention and that in some cases some features of my invention may be used without a corresponding use of other features.

Having now described my invention, what I claim as new and desire to secure by Letters Patent, is:

1. In a sewing machine, the combination with the stationary frame work, of work guiding mechanism mounted thereon and comprising a sliding body formed with a slot and provided with rack teeth alongside said slot, an axle member passing through the slot in said body and screwed at its inner end into said frame work and formed at its outer end with an enlarged head portion, a knob journaled on said axle member and comprising a spur gear portion meshing with said rack teeth, said knob being formed with a central passage of which a portion adjacent the frame work fits about, and forms a bearing on said axle member while an outer portion is enlarged to form an elongated spring receiving space surrounding the outer portion of said axle member, and a helical spring located in said space and surrounding said axle member and acting between said knob and the head of said axle member to frictionally grip said body between said knob and frame work and thereby to frictionally hold said knob and body in their different adjustments.

2. In a sewing machine, the combination with the stationary frame work, of work guiding mechanism mounted thereon and comprising a sliding body formed with a

slot and provided with rack teeth alongside said slot, a knob comprising a spur gear portion meshing with said rack teeth, a stud passing through the slot in said body and secured at its inner end to said frame work, a spring acting between said stud and knob, whereby said body is frictionally gripped

between said knob and frame work and the knob and body are thereby frictionally held in their different adjustments and a work 10 engaging wear plate detachably clamped to the end of said body.

RAYMOND L. PLUMLEY.
